UNITED STATES PATENT OFFICE.

ABBOT AUGUSTUS LOW, OF BROOKLYN, NEW YORK.

PUNCH.

SPECIFICATION forming part of Letters Patent No. 600,587, dated March 15, 1898.

Application filed December 21, 1896. Serial No. 616,418. (No model.)

To all whom it may concern:

Be it known that I, ABBOT AUGUSTUS LOW, a citizen of the United States, residing in the city of Brooklyn, in the county of Kings and State of New York, have invented certain new and useful Improvements in Punches, of which the following is a specification sufficient to enable others skilled in the art to which the invention appertains to make and use the same.

My improvements relate to devices for stamping or perforating cards by hand, as set forth in my concurrent application, Serial No. 610,919, filed November 3, 1896, in which the novelty consists, primarily, in combining and arranging with a hand-punch a rectangular gage which is adjustable both laterally and longitudinally with relation to the canceling device for governing the position in which the card is to be presented to the latter.

My present invention is designed to facilitate the adjustment of the parts, as well as the introduction, support, and removal of the cards to be canceled; and it consists in the special construction and arrangements of parts hereinafter described and claimed.

In the accompanying drawings, Figure 1 is a plan of my improved device. Fig. 2 is a view of the under side of the same. Fig. 3 is a side elevation; Fig. 4, a sectional elevation on plane of line 4-4, Fig. 1; Fig. 5, a front view of the device; Fig. 6, a sectional elevation, upon an enlarged scale, of the spring-bolt; Fig. 7, a plan of a portion of a card.

A is the punch-lever, carrying the usual die or other canceling device. The other lever B is formed with two jaws B' B'', the lower one, B'', forming an anvil and being perforated to receive the die. The levers A B are held apart in their normal position by the spring C.

The lower jaw B'' is formed with a series of screw-holes d, arranged longitudinally, with any one of which the set-screw D may be made to engage. This set-screw D is used to clamp and hold the bracket E to the lower jaw of the punch, said bracket being adjustable longitudinally thereon through the medium of the holes d, which are spaced to cor-

respond to the distances between the side spaces on the card which is to be canceled.

An upper arm e of the bracket E carries a spring-bolt F, the lower end of which engages with any of the series of holes g in the gage G when brought into coincidence therewith.

The gage G is formed with the lower transverse member g', having the longitudinal slot g², through which the stem of the set-screw D passes, so that the gage may be freely adjusted laterally in either direction when the set-screw is loosened.

Supported upon the transverse bar g' is the upper parallel transverse member g³ of the gage-piece G, in which the series of holes g⁵ are formed. Extending upward from either end of the upper transverse member g³ are the guiding-arms g⁴ g⁵, which support between them the skeleton floor g⁶, consisting of the semicircular member g⁷ with its radial arms g⁸. The inner edge of the arm g⁴ flares outward to facilitate the introduction of the card and to act as a guide to conduct it squarely into position, while the other arm g⁵ is formed with a vertical lip g⁹, against which the opposite end of the card readily finds a bearing. The semicircular member g⁷ facilitates the insertion and removal of the card by affording a free and unobstructed space for the fingers.

The operation of adjusting the gage so that it shall present a given space upon the card for cancellation is as follows: The bracket-piece E is set back or forward, as the case may be, to correspond with the distance from the edge of the card of the rows of spaces one of which it is desired to cancel, the set-screw being withdrawn for this purpose and then reinserted to engage with the corresponding hole d in the series formed in the lower jaw B''. The lateral adjustment of the gage is effected by withdrawing the spring-bolt F and sliding the gage laterally in either direction until the particular space desired is brought into coincidence with the punch, when the spring-bolt is allowed to engage the corresponding hole g in the series formed in the upper transverse member g³, thereby locking the gage against movement in any direction.

By my present construction of adjustable gage the cards may be more quickly and conveniently brought into position for cancellation with less skill on the part of the operator than heretofore required.

What I claim as my invention, and desire to secure by Letters Patent, is—

1. In combination with a hand-punch substantially such as described, the bracket-piece E, adjustable longitudinally on the lower jaw of the punch, and carrying the spring-bolt F, and the transversely-adjustable gage G, arranged and operated substantially in the manner and for the purpose described.

2. In combination with a hand-punch substantially such as described, formed with the longitudinal series of holes d, in its lower jaw, the bracket E, formed with the spring-bolt F, the set-screw D, and the gage G, formed

with the lower transverse member g', having the longitudinal slot g², and the upper transverse member g³, formed with the series of perforations g, together with the forwardly-projecting arms g⁴, g⁵, the whole arranged and operating substantially in the manner and for the purpose described.

3. In combination with a hand-punch and bracket E, adjustable longitudinally on the lower jaw of said punch and carrying the spring-bolt F, the laterally-adjustable gage G, formed with the gage-arms g⁴, g⁵, and skeleton floor g⁶, having the semicircular member g⁷, for the purpose and substantially in the manner described.

ABBOT AUGUSTUS LOW.
